UNITED STATES PATENT OFFICE.

FRANK W. ROYSTER, OF WILMINGTON, NORTH CAROLINA.

GARBAGE-RECEPTACLE.

1,263,604.

Specification of Letters Patent. Patented Apr. 23, 1918.

Application filed April 7, 1917. Serial No. 160,571.

To all whom it may concern:

Be it known that I, FRANK W. ROYSTER, a citizen of the United States, and a resident of Wilmington, in the county of New Hanover and State of North Carolina, have invented new and useful Improvements in Garbage-Receptacles, of which the following is a specification.

This invention relates to a garbage receptacle and has particular reference to a device of this character which is placed in the ground and kept closed so as to exclude flies and other vermin therefrom, provision being made for readily opening the receptacle when it is desired to place garbage therein.

A further object of this invention is to provide a receptacle for garbage or other trash which will not allow the escape of obnoxious and unhealthy odors therefrom.

20 A still further object is to provide a receptacle for a garbage can which will protect same from ill treatment and weather.

Other objects and advantages will be apparent from the following description, taken 25 in conjunction with the accompanying drawings and the particular features of novelty will be pointed out in the appended claims.

In the drawings, in which similar characters of reference denote similar parts in all 30 the views,

Figure 1 is a plan view of the device,

Fig. 2 is a side view of the device certain parts being shown in section,

Fig. 3 is an end view of the device, certain parts being shown in section,

Fig. 4 is a view of the operating levers,

Fig. 5 is a perspective view of the frame of the cover,

Fig. 6 is a side elevation of a portion of 40 the frame of the cover.

Referring more particularly to the drawings, a receptacle 1 of suitable material, such as concrete, is provided which is placed in the ground with the upper edge of same substantially flush with the surface of the ground. The upper portion of the receptacle 1 is tapered downwardly as shown clearly in Fig. 2. The receptacle 1 is adapted to receive a garbage can 2 of any ordinary construction, the upper edge of the receptacle being provided with a flange 3 which receives a frame 4, which is hinged to the top of the receptacle 1 at 5.

As shown in Fig. 5, the frame 4 is provided with oppositely disposed depending arms 6. Extending between the arms and secured thereto is a rod 7. One of the sides of the frame 4 is beveled as shown by 8 in Fig. 5 to permit the frame to swing upwardly without contacting with the side of the receptacle 1. Mounted in the frame 4 and extending into the receptacle 1 are spouts 9 and 10 which are provided with similar sides 11 and 12. The spout 9 is pivoted on a shaft 13 which is journaled in opposite sides of the frame 4, while the spout 10 is pivoted on shaft 14, likewise journaled in opposite sides of the frame.

As shown in Figs. 1 and 2 when the spouts 9 and 10 are in their normal position, or closed, the upper side of each spout is substantially in the same longitudinal plane with the frame 4 and the upper edge of the receptacle 1 and the edges of the spouts fit closely together. Mounted on the frame 4 is a hook 15 which is adapted to be swung over the two adjoining edges of the spouts 9 and 10, to hold the same when the frame 4 is raised.

Pivotedly mounted on the shaft 7 and adjacent the inner sides of the depending arms 6 are levers 16 which are as shown for a portion of their length arcuate shaped. The rod 7 extends through these levers near one end of same and the other end of these levers is provided with a plurality of rollers 17. Mounted on the depending arms 6 in brackets 18 are push rods 19 carrying at one end a head 20. The lower ends of the rods 19 terminate in an enlarged portion 21 from which extend angularly disposed arms 22. The upper ends of the rods 19 extend above the top of the frame 4. Secured to the end of each arm 22 is a link 23 which is secured to the ends of the levers 16 as shown clearly in Fig. 4. As shown in Fig. 3, the rollers 17 are disposed toward each other and as shown in Fig. 2, these rollers serve to support the spouts 9 and 10 and limit the downward movement of same.

Mounted on the frame 4 is a handle 24 for assistance in raising the frame. It is obvious that the enlarged portion 21 being positioned below the bracket 18 will limit the upward movement of the rod 19 by 105 wedging against said bracket.

From the above description, it is obvious that the operation of the device is as follows:

With the parts assembled as shown in the drawings, the rods 19 are moved downwardly which, because of their connection with the levers 16 pivoted on shaft, will cause the longer arms of said levers to move upwardly, forcing the spouts 9 and 10 upwardly upon their pivots 13 and 14 as shown by dotted lines in Fig. 2. The garbage or other trash may then be dumped into the spouts 9 and 10 from where it will pass into the can 2. Upon the release of the rods 19, it can be readily seen that the weight of the long arms of the lever will allow same to drop and allow the spouts 9 and 10 to resume their normal position.

It is obvious that by this device, I have constructed a receptacle for garbage or other trash which will fulfil the objects above mentioned and which is easy and inexpensive to manufacture, and strong and durable in operation, but I desire it understood that various minor changes in the form and proportion may be made that may fairly fall within the scope of the invention without departing from the spirit of said invention.

Having thus described my invention, what I claim as new and desire to secure by Letters Patent is,

1. In a device of the class described, in combination a receptacle, a frame secured to the upper portion of said receptacle, spouts pivoted at opposite ends of said frame, the upper edges of said spouts lying adjacent each other, depending arms secured to the frame at opposite sides thereof, a shaft secured to and between said arms, a plurality of levers mounted on said shaft, and means secured to the arms for raising said levers.

2. In a device of the character described, a receptacle, a frame hingedly secured to the top of the receptacle, spouts pivotally mounted in said frame near the opposite ends of same, depending arms secured to the frame, a shaft secured to and between said arms, a plurality of levers mounted near opposite ends of said shaft, rollers carried by said levers at their longer ends, a rod secured to each of said depending arms and connected to the short arm of each of said levers, and a receptacle positioned within the first named receptacle.

FRANK W. ROYSTER.
